UNITED STATES PATENT OFFICE.

EDWIN A. NEWMAN, OF WASHINGTON, DISTRICT OF COLUMBIA, ASSIGNOR
TO THE NEWMAN ANTI-FREEZING WATER PIPE COMPANY, OF CHICAGO,
ILLINOIS.

ANTI-FREEZING DEVICE FOR WATER-PIPES.

SPECIFICATION forming part of Letters Patent No. 389,098, dated September 4, 1888.

Application filed November 5, 1887. Serial No. 254,414. (No model.)

To all whom it may concern:

Be it known that I, EDWIN A. NEWMAN, a citizen of the United States, residing at Washington, in the District of Columbia, have invented certain new and useful Improvements 5 in Electro-Thermostatic Anti-Freezing Apparatus for Water Pipes, of which the following is a specification.

The object of my invention is to provide 10 improved apparatus for the automatic cut off of water from the service pipes of a building, and for draining them at times when the temperature has fallen to such a degree that the water in the pipes is liable to freeze.

Another object of my invention is to provide 15 means for temporarily turning on the water to the service-pipes when it is wanted after it has been turned off by the thermostatic apparatus.

My invention consists in certain novel 20 apparatus and organizations of apparatus adapted to attain the objects of my invention. Certain features of the invention are deemed 25 novel irrespective of their application to the apparatus to which they are herein shown as applied.

The subject-matter claimed will be herein-after designated.

In the accompanying drawings, Figure 1 is 30 a diagram view of one form of my improved apparatus, showing some of the apparatus partly in section. Fig. 2 is a diagram view of another form, with some of the apparatus partly in section. Fig. 3 shows another modified form of apparatus. Fig. 4 is a vertical central section of the valve and valve-operating mechanism shown in Fig. 3. Fig. 5 is a plan view of the valve-seat, with the casing broken away, of the valve shown in Figs. 3 35 and 4. Fig. 6 is a bottom view of the valve shown in Figs. 3 and 4, and Fig. 7 is a bottom view of the switch-blocks of the faucet which is preferably employed in my improved pipe system.

Referring first to Fig. 1, Th indicates a 40 thermostat that may be of any suitable construction, and E² so much of a cock or faucet as is necessary to illustrate my invention. A contact-finger, E³, bears on the plug of the faucet, 45 and is connected by an electric conductor or

line-wire, a, to the thermostat Th. The faucet is provided with a plug, E², of insulating material, so that when the faucet is turned to a position to have the finger E³ bear on the plug the electric circuit will be broken. The 55 faucet is shown as provided with a ventilating-valve, o, the operation of which is described in my application for Letters Patent filed November 5, 1887, No. 254,413. The object of the ventilating valve is to admit air to 60 the pipes to facilitate draining the water from them.

D⁵ indicates a water-trap, such as is often used in a pipe system. At the bottom of the bend of the trap I connect a drain-pipe, D⁶, 65 and between the trap and the drain-pipe I arrange a valve, preferably formed of a disk, d¹, secured to a stem, D⁴. The valve rests on a valve-seat, d⁵, to which is secured a stud, d⁶, that projects through a perforation, d⁷, at one 70 side of the disk. The stud d⁶ fits loosely in the perforation, so that the disk may rock up and down on the stud as a pivot.

The valve-stem D⁴ is secured at its lower end to the armature D³ of an electro magnet, D². 75 The magnet is mounted on the pipe D⁶, and is suitably insulated therefrom, as indicated. The core of the magnet projects into the pipe, and its end is in close proximity to the armature. When the magnet is not energized, the 80 stem will hang vertically and the armature will be held away from the magnet. The valve will then be closed; but when the magnet is energized the armature will be attracted and the valve will be opened, as indicated in the drawings. When the valve is open, the water will 85 pass from the trap into the drain-pipe D⁶, and thence to a sewer or other conduit. The line-wire a runs from contact a' to one pole of battery C B and from the other pole to the electro-magnet D². From the magnet D² the wire 90 runs to the coils of the magnet A' of the apparatus for controlling the valves between the street-main and the service-pipes and between the service-pipes and the drain-pipe. 95

A⁶ indicates a pipe connected to the street-main, and A⁷ the service-pipe. The valve A⁴ when closed rests on a valve-seat, A⁵, and closes communication between the main and the service-pipe. The valve A⁸ when closed rests on a 100

valve-seat, A⁷, and closes communication between the service-pipe and the drain-pipe A⁹, which extends through the electro-magnet A' and forms its core. The valves A⁴ and A⁸ are connected, as shown, by a rod or spindle, A³, which passes through the pipe A⁹ and connects them with the armature A² of the electro-magnet A'. The spindle A³ extends through the valve A⁴ and is supported and guided in lugs 10 or cross-bars A¹⁰ in the pipes. It will be observed that when the valve A⁴ is closed the valve A⁸ is open, and vice versa. The pipes are all connected by a suitable coupling, A¹¹, within which is the valve-chamber. The coils 15 of the magnet A' are inclosed by a metallic casing, A¹¹. A series of resistance-blocks, a³, is arranged in a frame, a⁴, of non-conducting material, which is adjustably attached to the casing A¹². The end block, a⁵, is connected 20 electrically with the coils of the magnet A'. The armature A² carries a spring contact-finger, a², that is moved back and forth by the armature over the resistance-blocks. The armature is electrically connected by the spindle A³ and the pipes, as shown by dotted lines, 25 to the faucet E'. If the armature A² be withdrawn from the magnet, the finger a² will rest on the resistance-block a⁵, so that a maximum current may pass; but as the armature approaches the magnet the finger passes over the 30 blocks, so as to throw in more and more resistance until the armature is home, when the minimum current will pass. As is well known, a feeble current will be sufficient to hold the 35 armature home, while a much stronger current is necessary to draw it from a distance. This arrangement enables me to save battery.

The operation of the apparatus is as follows: Suppose the temperature is high and there is 40 no danger of the pipes freezing; the electric current will then be broken between the thermostat Th and the contact a', so that no current can pass through the magnets A' and D². The valve A⁴ will then be held open by the 45 water-pressure and the valve A⁸ closed. The valve d⁴ in the trap will also be closed. But suppose the temperature to be low and the thermostat to be in electrical connection with the contact a', the faucet E' to be closed, and 50 the finger E³ resting on the metallic part of the faucet; an electric current will then run from one pole of battery C B to electro-magnet D²; thence to electro-magnet A', resistance-blocks a³, finger a², armature A², spindle A³, 55 to pipes; thence to faucet E', finger E³, thermostat Th, contact a', and back to battery. The armature A² will be drawn home, and will thereby close valve A⁴ and open valve A⁸. The armature D² will also be drawn home and 60 will open valve d⁴, so that the water-supply will be cut off from the house-pipes and the drain-pipes opened, so that the water in the house or service pipes, as well as in the traps, &c., will be allowed to escape. The 65 valves will remain in this condition as long as the weather is cold enough to freeze the pipes. When it grows warmer, the electric circuit

will be broken at the thermostat and the valves will assume their normal position. If while the weather is cold it is desired to draw water 70 from the faucets, the electric circuit may be broken as soon as the faucet is turned till the finger E³ rests on the plug E², so that the magnets will be demagnetized and the valve A⁴ will open and the drain-valves close. When 75 the faucet is turned back, the valves will be returned again.

I will now describe a modification of my apparatus shown in Fig. 2. This apparatus is so arranged that the electric current is used 80 only at the instant of energizing the magnets. Just after they are energized and have attracted their armatures the current is broken. By such an arrangement there is but little consumption of battery, which will consequently last a long time and need but little attention. In this figure, Th represents a thermostat, R⁴ the upper part of a cock or faucet, R³ the valve stem, R² a metallic switch-block connected to the casing of the faucet, and R' a switch-block, the body of which is formed 85 of insulating material and is provided on its upper and lower faces with metallic rings a⁸ and a⁹, respectively, which project from the block and respectively make contact at times 90 with the casing R⁴ and the metallic block R². The faucet shown in the drawings is of that class in which the valve-stem is raised and lowered to open and close the valve. When the stem is raised, the ring a⁸ makes contact 95 with the faucet-casing. When the stem is lowered, the ring a⁹ makes contact with the block R². The circuit-wire a is electrically connected to the ring a⁸ and passes to the electro-magnet D², arranged below the bend of the 100 trap D⁵. The circuit then continues to contact a', and, when the thermostat is closed, through the thermostat and battery C B, to the coils of the electro-magnet A'. A circuit-wire, a^x, is connected to the ring a⁹ on the switch-block R' on the faucet and runs to an electro-magnet, D⁸, arranged beneath the trap D⁵, by the side of the magnet D². The cores of the magnets D² and D⁸ project into a 105 valve-casing, D⁹, arranged between the trap and the drain-pipe D⁶. A valve, d⁴, normally 110 rests on a valve-seat just below the trap and over the casing. Within the casing is an arm, D¹⁰, pivoted at its lower end, and provided at its upper end with a cam, d¹⁰, in contact 115 with a stud, d¹¹, on the bottom of the valve d⁴. In the drawings the valve is shown closed; but if the arm D¹⁰ be swung on its pivot over to the other side of the casing the cam will raise the stud d¹¹, and thus open the valve d⁴. 120 The arm D¹⁰ constitutes the armature of the electro-magnets D² and D⁸. When the magnet D² is energized and the magnet D⁸ de-energized, the armature will be attracted to a 125 position to hold the valve d⁴ open. When the magnet D⁸ is energized and the magnet D² de-energized, the armature will be attracted to a 130 position to allow the valve to remain closed.

Referring to the apparatus for controlling

the valves between the street-main, the service-pipes, and the drain-pipe, A⁶ indicates the pipe connecting with the street-main, A⁷ the service-pipe, and A⁸ the drain-pipe. A⁴ is a valve designed to open and close communication between the main and the service pipe and between the service-pipe and the drain-pipe. The valve A⁴ is connected by a rod or spindle, A³, (which passes through the core of the magnet A') with the armature A², which is preferably cup-shaped, as shown. The pipes A⁶, A⁷, and A⁸ are connected by a coupling, A¹¹, which is provided with an annular series of openings, a¹¹, and a chamber, a¹², between the pipe A⁶ and the pipe A⁷. An opening, a¹³, is made in the coupling, which opens communication between the pipe A⁷ and a chamber, a¹⁴, that connects with the drain-pipe A⁸. If the armature be withdrawn from the magnet, as shown in the drawings, there will be communication between the main and the service-pipe, and connection between the service-pipe and the drain-pipe will be closed; but if the armature be drawn home the valve A⁴ will be moved beyond the openings a¹¹, so that the communication between the main and the service-pipe will be closed and communication between the service-pipe and the drain-pipe will be opened.

30 F² indicates an electro-magnet mounted on the coupling A¹¹ just over the electro-magnet A'.

F' indicates a gravity-catch adapted to engage with the armature A² when it is home and hold it fast. An arm, f³, of the catch carries the armature f⁴ of the electro-magnet F², and also a spring contact-finger, f², that moves over a block of insulating material, F³, and a metallic contact-plate, f³. The plate f³ is electrically connected with the coils of the magnet F², which is in turn connected by line a⁸ with battery C B', electro-magnet D⁸, and ring a⁸ in the faucet. The block F³ and plate f³ are curved, so as to allow the finger f² to move back and forth freely.

On the casing of the magnet A' is secured an insulating block, a⁶, which carries a metallic plate, a⁵, electrically connected with the coils of magnet A'. A finger, a⁴, is secured to armature A², and is moved back and forth by the armature over block a⁶ and plate a⁵. When the armature is withdrawn, the finger a⁴ rests on the plate a⁵, and if the electric circuit be closed at the thermostat and at the faucet a current will run from battery C B to coils of magnet A', to plate a⁵, to finger a⁴, to armature A², to pipes, to faucet, as shown by dotted lines; thence by wire a to magnet D², to contact a', through thermostat, back to battery. 55 This will energize the magnet A' and the armature A² will be drawn home. Just before it is fully drawn home the catch F' drops, so that the armature cannot return. When the armature is fully drawn home, the finger a⁴ will have passed off from the plate a⁵, so that the electric circuit is broken; but, as above remarked, the armature is held in place by the catch F.

The current will also energize the magnet D², which will attract the armature D¹⁰, and thus open the valve d¹ in the trap D⁵. When contact is broken at the thermostat or at the faucet, the magnets A' and D² will be demagnetized; but the valve A⁴ is opened by a separate circuit, and by which also the valve d¹ is closed. This circuit runs from battery C B' to magnet F², to plate f³, to finger f², to catch F'; thence through coupling A¹¹ and pipes to faucet and ring a⁸, when said ring is in contact with the casing of the faucet. From the ring a⁸ the circuit runs to magnet D⁸, and thence to battery C B'. It will be seen that in the act of opening the faucet the electric circuit is closed, so as to close the valve d¹ and withdraw the catch F'. At the same time the circuit a is broken at the faucet and the magnets D² and A' are demagnetized. The water-pressure will then force back the valve A⁴ and hold the armature away from the magnet. As soon as the armature f⁴ is home the circuit is broken between finger f² and plate f³. The nose f' rests on the armature A² and holds it up until the armature is drawn home. Instead of employing a magnet for elevating the catch, a pull-cord, F', may be used.

The operation of the apparatus has been sufficiently indicated in the above description.

The great utility of this form of apparatus is its economical use of battery. When the circuit is broken at the thermostat, no current can pass through either circuit. The circuit a is broken at the contact a', and the circuit a⁸ will be broken as long as the catch F' is raised—i. e., as long as the armature A² is away from the magnet, which position it always occupies when the circuit is broken at the thermostat. When the circuit is closed at the thermostat, the valves will be automatically operated, as above described, and may be opened and closed at the faucet in the act of turning the water on or off in the usual way.

In Figs. 3, 4, 5, and 6 I have shown a modified form of apparatus, by which the valve between the street-main and the service-pipe and between the service-pipe and the drain-pipe may be operated by electro-magnets using a minimum amount of current in a somewhat different way from that shown in Fig. 2.

A⁶ indicates the pipe connecting with the main; A⁷, the service pipe, and A⁸ the drain-pipe.

A⁴ represents a valve adapted to open and close communication between the main and the service-pipe and between the service-pipe and the drain-pipe. The valve A⁴ is in this instance circular, as shown in Fig. 6, and provided on opposite sides with openings A¹⁵. On its under side the valve is formed with a hollowed-out chamber, A¹⁶, extending transversely across the valve between the openings A¹⁵ nearly to the edge on each side. The valve A⁴ rests on a horizontal valve-seat, A⁵, provided with a central opening, a¹⁴, connecting with the drain-pipe, and on each side with openings a¹², which register at times with the

openings A^{15} in the valve. When the openings do so register, communication is established between the main and the service-pipe, as indicated in the drawings, and the drain-pipe is closed; but when the valve is given a quarter-turn the chamber A^{16} registers with both the openings a^{12} , and the entrance to the drain-pipe and the openings A^{15} are closed by the solid part of the valve-seat, so that no water can enter from the main, and the water in the service-pipe will pass through the openings a^{12} into the chamber A^{16} and out through the drain-pipe.

The valve A^4 is connected by a valve-spindle, A^3 , to an armature, A^2 , below the electro-magnets A' and A^x . The armature is preferably formed of two wings united at their inner ends and secured to the spindle A^3 . A plan view of the armature is shown by dotted lines in Fig. 3. The wings face in opposite directions, and their upper faces are tapered or inclined from their outer ends upward, as shown in Fig. 4, so that when the extreme outer ends of the armature-wings are opposite the magnets the attractive force will be exerted along the inclined surface, causing the armature to turn until the upper plane surface is reached. The movement of the armature will of course correspondingly turn the valve. I have shown two vertical horseshoe electro-magnets arranged with their legs side by side equal distances apart, but crossing each other. The cores of the magnets are so arranged that a single pair of magnets will act correspondingly on the opposite wings of the armature. The spindle A^3 is surrounded by suitable packing, x , but is free to turn therein. Above the armature and secured thereto is a switch-block, G , of insulating material and provided with a metallic contacting ring, g , on which spring contact-fingers a^6 and a^7 bear at all times. Above the ring g are curved plates g' , each equal to a quarter of the surface of the block and arranged on opposite sides thereof. The plates g' are in electrical connection with the ring g , preferably being formed integrally therewith. Spring contact-fingers a^8 and a^9 bear at times on the plates g' and at times on the surface of the block between the plates. The ring and plates are sunk into the block so that their outer surfaces coincide. The finger a^6 is arranged diagonally opposite to the finger a^8 , so that they will be on corresponding plates g' at the same time. The fingers a^7 and a^9 are similarly arranged. The frame and casing of the apparatus may be of any suitable construction. I preferably form an annular brass base piece, G' , over pipes and on it mount a plate, G^2 , of insulating material. The magnets are mounted on the plate G^2 , and are covered by a casing, G^3 , secured at the top to the metallic connection between the cores of the magnets.

Referring to Fig. 3, M^3 indicates a switch-plate of insulating material, provided with a hand-switch, m^3 . Two contact-buttons, m^4 m^5 , are arranged on one side of the plate in close

proximity to each other, so that the switch may close an electric circuit between them. Similar buttons, m^6 m^7 , are arranged on the opposite side of the plate. A circuit-wire, a , runs from button m^6 to thermostat Th , thence to battery CB , thence to spring-finger a^6 , thence to ring g on the switch-block to plate g' , to finger a^8 , to coils of electro-magnet A' , and thence by wire a to button m^5 . When an electric circuit is closed through this circuit, the valve A^4 will be closed—i. e., the water will be cut off from the main and the drain-pipe will be opened. Of course, if the circuit is not closed at the thermostat, the magnet will not be energized. In the drawings the circuit is supposed to be open at the thermostat. Another circuit runs from button m^4 by wire a^x to finger a^7 , to ring g , to plate g' , to finger a^9 , to coils of electro-magnets A^x , to line d^4 , through battery CB' , to button m^5 . If the circuit be closed, the magnets A^x will be energized and will turn the valve so as to turn on the water and close the drain-pipe. The most important feature of this construction is, that immediately after the magnets are energized and the armature has been given a quarter-turn the electric circuit is broken by reason of the fact that the plates g' go past the ends of the contact-fingers a^6 and a^8 and a^7 and a^9 , so that the current is only used for an instant. This is true of either circuit.

The operation of the apparatus has been indicated in the above description; but to further explain: Suppose that the temperature falls and the circuit a is closed at the thermostat; the magnets A' will immediately be energized and will turn the armature so as to shut the valve A^4 . Immediately after the valve is closed the circuit is broken, the contact-plates g' having left the contact-fingers a^6 and a^8 of this circuit and made contact with the fingers of the other circuit. The valve will remain stationary until the other circuit is closed at the hand-switch, when the magnets A^x will be energized and the valve again opened. By this arrangement the valve may be opened and closed at pleasure.

If the thermostat be omitted, the valve may be opened and closed at pleasure by simply shifting the hand-switch; but when the thermostat is included in the circuit for closing the valve the circuit will be closed automatically at the thermostat to shut the valve when the temperature falls to the freezing-point.

My improved apparatus is especially designed for use in a pipe system; but some parts of it are obviously more extended in their application.

The apparatus may be connected in the circuit of an electric-light system, by which powerful currents may be utilized to operate the valves.

I claim as of my own invention—
1. The combination of the main, the service-pipe, a valve for opening and closing communication between the main and the service-pipe, the electro-magnet, the armature of the

5 electro-magnet connected to the valve, the electric circuit, including the coils of the electro-magnet, the faucets in the service-pipes, and the circuit making and breaking devices operated by the faucets, substantially as set forth.

10 2. The combination of the main, the service-pipe, a valve for opening and closing communication between the main and the service-pipe, the electro-magnet, the valve spindle, the armature of the electro-magnet connected to the valve-spindle, the electric circuit, including the coils of the electro-magnet, the thermostat for automatically making and breaking the circuit, the faucets in the service-pipe, and the circuit making and breaking devices operated by the faucets, substantially as set forth.

15 3. The combination of the main, the service-pipe, the drain-pipe, a pipe-coupling connecting the main, the service-pipe, and the drain-pipe, a valve within the coupling for opening and closing communication between the main and the service-pipe and between the service-pipe and the drain-pipe, the valve-spindle, the electro-magnet, the armature of the electro-magnet connected to the valve-spindle, and the electric circuit, including the coils of the magnet, substantially as set forth.

20 4. The combination of the main, the service-pipe, the valve for opening and closing communication between the main and the service-pipe, the electro-magnet, the valve-spindle passing through the core of the magnet, the armature carried by the valve-spindle, the electric circuit, the contact-finger carried by the armature and moving coincidently therewith for making and breaking the circuit, and the thermostat included in the circuit, substantially as set forth.

25 5. The combination of the main, the service-pipe, the drain-pipe, a valve for opening and closing communication between the main and the service-pipe and between the service-pipe and the drain-pipe, the electro-magnet, the valve-spindle passing through the core of the 40 magnet, the armature of the electro-magnet secured to the valve-spindle, the electric circuit a^1 , including the pipes, the thermostat for automatically making and breaking the circuit, the faucet, the switch-block, the contact-ring a^2 , for making and breaking the circuit at the faucet, the electro-magnet F^1 , its armature, the catch operated thereby, the electric circuit a^3 , including the pipes and the magnet F^2 , and the contact-ring a^4 , for making 45 and breaking the circuit a^5 at the faucet, substantially as set forth.

50 6. The combination of the main, the service-pipe, the valve for opening and closing communication between the main and the service-pipe, the electro-magnet, the valve-spindle passing through the core of the magnet, the armature of the electro-magnet secured to the valve-spindle, the sewer-trap, the valve in the bend of the trap, the electro-magnet for operating the valve, the electric circuit, including the coils of the electro-magnets, the thermostat for automatically making and breaking the circuit, the faucet, and the circuit making and breaking devices operated by the faucet, 55 substantially as set forth.

In testimony whereof I have hereunto subscribed my name.

EDWIN A. NEWMAN.
